CALENDAR

Howard L. Fischer, St. Paul, Minn., assignor to
Brown & Bigelow, St. Paul, Minn., a corpora-
tion of Minnesota

Application September 29, 1928, Serial No. 309,147
Renewed September 12, 1933

12 Claims. (Cl. 40—107)

My invention relates to calendars, being particularly adapted to that type of calendars where a casing is provided which holds a series of plates or discs slideable within the casing. A primary feature of the invention is to provide means for closing one opening of the calendar casing when the other opening is open to expose the date.

My calendar includes a rotatable casing having slideable members within the same upon which the days of the month are designated by numerals or otherwise and wherein the casing is provided on each slide with openings to disclose the numerals. When the casing is rotated the plates are adapted to slide into position to expose the proper date through the opening in the casing on the front of the same, and I provide means for automatically closing and opening the other side or back of the casing so that when one side of the casing is opened to disclose the date, the other side is closed.

My calendar is automatic and perpetual, being adapted to be readily set for the particular day of the month and to indicate the date when set.

These features, together with other details and objects of the invention will be more fully and clearly set forth hereinafter. In the drawing forming part of the specification:

Figure 1 is a perspective view of my perpetual calendar as it would appear in use.

Figure 2 is a side view of the same showing the rotation of the rotatable member.

Figure 3 is also a side view of the partial rotation of the rotatable member.

Figure 4 is a section longitudinally through the rotatable member.

Figure 5 is a detail of one of the closures for the rotatable member.

Figure 6 is another form of closure for the rotatable member.

My automatic perpetual calendar A is provided with a base B of a suitable nature to support the standards 10 projecting upward from each side of the base B. The standards 10 are adapted to pivotally support the rotatable member C by the studs 11 which extend through the side of the casing of the member C.

The rotatable member C is rotatable on the studs 11 as indicated by the arrow in Figure 2, and is formed with comparatively flat sides 12 and 13. The sides 12 and 13 are formed with display openings 14 and 15 respectively through which the slideable members 16 are adapted to be disclosed to display the particular day of the month such as is illustrated by the member 16 which indicates the numeral "1" indicating the first day of the month.

The rotatable member C, in its operation, rotates to permit the slideable plate members 16 to slide past the division member 17 positioned within the rotatable member C, through the open-

ings 18 on each side of the member 17. The opening 18 is virtually the same width as the thickness of the plate 16 so that only one plate 16 may slide through either of the openings 18 at one time, when the rotative display member C is rotated on its axis formed by the studs 12.

The base B may be provided with a rotatable display disc E, a portion of which is illustrated through the opening 19 in the front of the base so as to disclose the particular month of the year. In this manner the perpetual calendar may be operated to indicate any particular month in the base and any day, by the rotatable member C. The plates 16 are provided with numerals for each day of the month and thus if the rotatable member C is rotated, the plates 16 slide into position to indicate this numeral for the particular day, and thus can be set so as to provide a perpetual calendar.

In a perpetual calendar of this nature it is desirable to provide means for closing one of the openings 14 or 15 when it is in operable position to indicate the particular day desired. I have therefore provided in my perpetual calendar suitable automatically operable shutters or closures F, one for each side 12, and 13.

These closures or shutters F are adapted to be pivotally supported by the ears 20 so as to hang freely adjacent the sides 12 and 13 respectively and in the rotation of the member C these shutters are adapted to open and close the openings 14 and 15 in accordance with the position of the same.

It will be noted that the shutters F open automatically in the rotation of the member C so that when either the opening 14 or 15 is at the top and front of the calendar A, the shutter F will hang down with the inner surface 21 of the shutter exposed on the lower front portion of the member C. This surface may carry suitable display material such as 22 for advertising purposes or for monograms or any suitable display means. When the shutter F hangs in open position as is illustrated in Figure 1, it discloses one of the plates 16 through the opening 14, the other shutter F on the surface 13 which is at that time considered the back of the rotative member C, closes the opening 15 which is positioned on the opposite side to the axis or center of the rotative member C. Thus the back of the calendar A is closed when the front is open.

This is quite important as it discloses only one display side at one time for the same, and gives a desk utility of a neat and attractive nature.

My calendar A also provides means of automatically opening and closing the different sides of the calendar in the rotation of the same. The shutters operate automatically by gravity to rotate into open and closed position. In operative position the shutters F always hang down toward

the base B. This adds a suitable bearing weight to the sides of the rotor C, which has a tendency to hold the rotor C in proper upright position to disclose one of the openings 14 or 15, and to 5 display the particular date which the calendar is set to disclose, while the back is entirely closed, as will be readily apparent.

My calendar provides a utility for advertising purposes or for display or monograms or names, 10 or any other suitable display material on the inside 21 of the shutters F, and when either of the shutters are in position to close the back of the calendar, this display is closed toward the inside of the calendar A.

15 The shutters F may be formed rectangular from a single piece of material with projecting lugs 24 for pivotally supporting the same in the ears 20 to the rotor C, or these shutters F may be formed in other shapes such as illustrated in 20 Figure 6 so that a very attractive shutter structure may be provided for the sides of the rotor C.

In accordance with the patent statutes, I have 25 described my perpetual automatic calendar, and while I have illustrated the particular formation thereof, I desire to have it understood that this is only suggestive of a means of carrying out the principles of my invention, and that variations may be made within the scope of the following claims without departing from the spirit 30 of my invention.

I claim:

1. A calendar comprising a rotor having slideable display plates therein, openings in each side of said rotor, outside shutters pivotally attached 35 to said rotor for closing and opening said openings in the rotation of said rotor and display surfaces on the inside of each of said shutters.

2. A perpetual calendar including a rotor to indicate the day of the month, means for rotatably supporting said rotor, display openings formed in said rotor, and shutters supported on 40 said rotor for said openings adapted to automatically rotate through an axis of one hundred and eighty degrees to expose the inner surface 45 of the shutters when in open position.

3. A date indicator including a casing having a series of slideable plates with numerals to indicate the date thereon, openings in said casing to display said slideable plates and shutter means 50 hingedly secured to said casing to operate automatically to close the back of said date indicator when the front is opened, said shutters hanging downward, and providing a balancing means to hold said casing upright in operative position.

4. A date indicator including a rotatable casing having a series of slideable date indicating plates therein, means for pivotally supporting said casing, shutter members for the openings in said casing, and means for supporting said shutters in a manner to cause the same to hang 55 downward from the point of support, closing the back of said casing and opening the front of said casing automatically in the rotation of said casing.

5. A calendar having a rotor with slideable display members therein, openings in said rotor to disclose said display members on either side of said rotor, doors hingedly supported to the sides of said rotor to swing freely in the rotation of said rotor, one of said doors forming a closure for the opening on one side of said rotor and the other door hanging in open position to disclose 70 the display member through the opening in the

other side so that the sides of said rotor alternately form front and back portions for said calendar in the operation thereof.

6. A display device comprising a rotor, slideable displays within said rotor, openings on either side of said rotor for disclosing the displays there-through, closures for said openings having pivoting lugs formed thereon and ear members projecting from said rotor adapted to engage said lugs to hingedly support said closures in a manner to automatically operate to open and close said openings in said rotor.

7. A display device having a member adapted to be rotated with a series of displays held in said member in a manner to change position therein, 85 openings for disclosing said displays and closures for said openings having an inner display face thereon which is exposed when in open position adjacent the opening, displaying said displays in said member.

8. A calendar including a series of slideable members enclosed within a casing, openings in said casing for displaying said members, one opening being positioned on one end of said casing, and the other on the other end so that when 90 said casing is rotated, one opening is at the top of the casing and the other at the bottom, closures for said openings hingedly supported to said casing, each closure being adapted to hang downward so that the closure on the front of said 95 casing is in open position and the one on the back is in closed position.

9. A calendar comprising a casing, means for rotatably supporting said casing, slideable display plates within said casing, openings for disclosing 100 said display plates oppositely disposed in relation to the ends and sides of said casing, and closures formed with supporting lugs adapted to be hingedly supported to said casing to automatically 105 fold into open and closed position in the rotation of said casing, said closures hanging downward from the pivotal point of said casing and forming a bearing weight to hold said casing with one end upward, and the opening in the upper end open while the opening in the lower end is 110 closed and forms the back of said calendar.

10. A calendar comprising a rotor having slideable display plates therein, openings in each side of said rotor, one positioned on one end of the rotor and one on the other end, the display 125 opening appearing at the top of the rotor, and automatic shutters adapted to close the back opening at the bottom and expose the inner surface of the shutter on the front while displaying one of said plates through the top opening on the 130 front.

11. A perpetual calendar including a rotor member having a series of indicators within the same, openings adjacent the ends and on the display faces of said rotor, said openings being disposed 135 to expose the displays held within said rotor singularly when in displaying position, and shutters on either side of said rotor, the shutter on the rear side hanging to close the display opening in the back of said rotor.

12. A display device, including a rotor, having a pair of display faces on either side thereof, display openings formed in said display faces, automatically operated shutters carried by said display faces, one of said shutters hanging to 145 open said rotor while the other of said shutters hangs to close said rotor.

HOWARD L. FISCHER.
